US00D873269S

(12) **United States Design Patent** (10) **Patent No.:** **US D873,269 S**
Hu et al. (45) **Date of Patent:** **** Jan. 21, 2020**

(54) **COMMUNICATIONS GATEWAY**

(71) Applicant: **GREE ELECTRIC APPLIANCES, INC. OF ZHUHAI**, Guangdong (CN)

(72) Inventors: **Chunqing Hu**, Guangdong (CN); **Chunyue Xu**, Guangdong (CN); **Wenbing Ling**, Guangdong (CN); **Xue Zhang**, Guangdong (CN); **Huanlong Wu**, Guangdong (CN); **Jingjing Wang**, Guangdong (CN); **Yaxi Dong**, Guangdong (CN); **Sha Li**, Guangdong (CN); **Guangyu Chen**, Guangdong (CN)

(73) Assignee: **Gree Electric Appliances, Inc. of Zhuhai**, Guangdong (CN)

(**) Term: **15 Years**

(21) Appl. No.: **35/505,848**

(22) Filed: **May 11, 2018**

(80) **Hague Agreement Data**

Int. Filing Date: **May 11, 2018**

Int. Reg. No.: **DM/103050**

Int. Reg. Date: **May 11, 2018**

Int. Reg. Pub. Date: **Oct. 12, 2018**

(30) **Foreign Application Priority Data**

Nov. 15, 2017 (CN) 2017 3 0563323
Dec. 5, 2017 (CN) 2017 3 0613772
